UNITED STATES PATENT OFFICE.

EDWIN H. GRANTHAM AND JOHN B. CORNWALL, OF MOLINE, ILLINOIS, ASSIGNEES TO
BARNARD AND LEAS MANUFACTURING COMPANY, OF MOLINE, ILLINOIS, A
CORPORATION OF ILLINOIS.

ELEVATOR.

1,088,564.

Specification of Letters Patent.

Patented Feb. 24, 1914.

Application filed February 25, 1913. Serial No. 750,683.

To all whom it may concern:

Be it known that we, EDWIN H. GRANTHAM and JOHN B. CORNWALL, both residing at Moline, Rock Island county, Illinois, 5 have invented certain new and useful Improvements in Elevators; and we hereby declare that the following is a full, clear, and exact description thereof, reference being had to the accompanying drawings, which 10 form part of this specification.

This invention is a novel improvement in elevators especially designed for use by employees in factories in passing from one floor to another, and its object is to provide 15 an endless elevator which can be operated at very little cost, and by which individuals or packages can be lifted from one floor to another, or lowered from one floor to another, quickly and easily.

Generally speaking the apparatus comprises a stout endless belt to which are fastened, at proper intervals, platforms large enough to carry a man. This belt runs over broad pulleys at the top and bottom of its 20 run and is guided by means of a substantial steel frame connecting the bearings in which the head and foot pulleys are journaled. At 25 convenient distances above the platforms metal loops are attached to the belt for use 30 as hand-holds.

The present invention has particular reference to the construction of the steps or platforms on which the persons stand while ascending or descending. These platforms 35 are arranged in pairs, one platform in each pair being adapted for use on the ascending side of the belt and the other at the descending side thereof; such platforms being attached to brackets, which are pivotally connected to each other, and are also connected 40 with the belt in such manner that the brackets can pass around or over and under the pulleys, at the head and foot of the belt run without binding or jarring.

We will first explain the construction of 45 the elevator in detail with reference to the accompanying drawings; and then concisely state in the claims the parts and features of construction wherein the present invention 50 resides and for which protection is particularly desired.

While the invention as described is intended primarily as an elevator for operatives or workmen in mills and the like; it

is also readily adapted for raising and lowering objects from one floor or level to another.

In the accompanying drawings—Figure 1 represents a side elevation of the elevator, partly broken away. Fig. 2 is a side elevation of Fig. 1, partly broken. Fig. 3 is an enlarged section on line 3—3, Fig. 2, showing one of the platforms. Fig. 4 is a side elevation of Fig. 3. Fig. 5 is a section on line 5—5, Fig. 4, looking in the direction 65 of the arrow. Fig. 6 is an enlarged detail.

As shown the elevator comprises an endless carrier or belt 1, of leather or other suitable material, which runs over an upper pulley 2 and under a lower pulley 3. The 70 shaft 2^a of the upper pulley may be journaled in suitable bearings in a frame 2^b supported in any suitable manner upon the upper floor of the building; and shown as mounted upon an I-beam 2^c; while the shaft 75 3^a of the lower pulley 3 is journaled in a frame 3^b mounted on the basement or lower floor of the building. The shaft 2^a may be operated by means of a worm wheel 2^d meshing with a worm 2^e on a transverse shaft 2^f 80 mounted in suitable bearings and provided with pulleys 2^g which can be driven by a belt (not shown) from a suitable motor.

The foregoing parts may be of any suitable construction and are not specifically 85 claimed herein.

The upper and lower frames 2^b and 3^b may be connected by pairs of vertically disposed U-bars 4, which bars are set with their channels facing the edges of the belt, and 90 such channeled bars are used as guides for the platform or step brackets as hereinafter explained.

Attached to the belt 1 at suitable intervals apart are bars 5 which may be secured to 95 the belt by rivets or by nuts and bolts as indicated in Fig. 3. These bars project slightly beyond the side edges of the belt and have on their outer ends studs or journals 5^a upon which are pivotally hung the 100 brackets 6, and 6^x of pairs of brackets that support the pairs of platforms. Each bracket 6, 6^x is approximately triangular shaped and stands at right angles to the belt, and each has a short inwardly extending 105 arm 6^b which is pivoted on the adjacent stud 5^a and is provided with a stud 6^c on which is mounted an anti-friction roller 7

that engages the groove of the adjacent U-bar 4. Each of these rollers has its tread ^{7a} of such slant or bevel as will conform to the slant of the inside of the channel bars 4, while its flange ^{7c}, which acts as a side guide, is curved outward and backward from the tread or point of contact with the bar; and the tread of the roller is less in diameter than the inner width of the channel bar 4. This leaves the idle side of the roller tread free from the rear flange of the guide bar, thus permitting the roller to turn freely.

The main portion of each bracket 6, ^{6x} projects at the outer side of the belt, and there is a pair of these brackets or braces employed at each side of the belt to support each pair of platforms. The outwardly projecting portions of the brackets 6, ^{6x} are approximately triangular in form, and these brackets are pivotally connected, as shown in Figs. 4 and 5. As shown in side elevation, Fig. 4, each pair of brackets 6, ^{6x} resembles an X, and they are pivoted together at their intersection preferably by forming the brackets 6, which would be uppermost at the ascending side of the belt, with a stud ^{6e} that passes through a corresponding opening in the related bracket ^{6x}, which would be uppermost at the descending side of the belt. And these brackets are held together by means of a washer ^{6f} strung on the stud ^{6e}, and a pin ^{6g} transfixing the stud. The related opposite brackets 6, ^{6x}, in each pair are connected by a platform or step ^{8a}, and the opposite brackets ^{6x} are connected by a platform or step 8. It will be seen that the platforms are arranged in pairs, and as shown the platforms ^{8a} would be uppermost at the ascending side of the belt, where the platform 8 would not be used; and at the descending side of the belt the platforms ^{8a} would be uppermost, while the platforms 8 would not be used.

While the brackets and platforms are arranged in pairs and both platforms are parallel when in use, they are braced one from the other; and their supporting brackets are pivoted at their meeting points, so that they may adjust themselves to the changing position of the belt when passing over the pulleys; thus avoiding unnecessary friction and the objectionable falling or jarring of the platforms as they pass over or under the pulleys.

55 The operation of our elevator will be obvious from the foregoing description and the drawing, and needs no detailed explanation.

While we have described a belt as the preferred carrier for the platforms, it is obvious that the invention is not restricted to a belt, as other endless carriers could be substituted therefor.

What we claim is:

1. In an elevator of the character specified, the combination of an endless carrier,

pairs of opposite similar brackets pivotally connected together at a point beyond the carrier and pivotally connected near their inner ends to said carrier, and upper and lower platforms supported by said pairs of brackets.

2. An elevator of the character described comprising an endless carrier, pairs of grooved bars beside the carrier, opposed brackets pivotally connected together at a point beyond the carrier, and also pivoted to said carrier near their inner ends and having their inner ends operatively engaged with the said grooved bars, and a platform supported by said brackets.

3. An elevator of the character described comprising upper and lower pulleys, an endless carrier running thereover, grooved bars beside the vertical runs of the carrier, upper and lower brackets pivotally connected to each other at a point beyond the carrier and also pivotally connected near their inner ends to said carrier, means on the pivoted ends of the brackets slidably engaging the said grooved bars, and platforms supported on said brackets.

4. In an elevator of the character specified, the combination of upper and lower pulleys, an endless carrier running thereover, grooved bars beside the carrier, upper and lower brackets pivotally connected to each other at a point beyond the carrier and also pivotally connected near their inner ends to said carrier, and devices on the pivoted ends of said brackets slidably engaging said grooved bars.

5. In an elevator of the character specified, the combination of upper and lower pulleys, an endless carrier running thereover, and pairs of upper and lower brackets pivotally connected to each other at a point beyond the carrier and also pivotally connected near their inner ends to said carrier, and a platform supported by said brackets; with grooved bars beside the vertical runs of the carrier, and rollers on the pivoted ends of said brackets engaging said grooved bars.

6. An elevator of the character described comprising upper and lower pulleys, an endless belt running thereover, and grooved bars beside the vertical runs of the belt; with pairs of pivotally connected upper and lower brackets, the brackets in each pair being pivotally connected together in front of the carrier and each bracket being pivotally connected at its inner end to the belt, rollers on the pivoted ends of the brackets engaging the grooved bars, and upper and lower platforms attached to said brackets.

7. An elevator comprising upper and lower pulleys, an endless carrier running over said pulleys, transverse bars connected to said carrier, pairs of brackets projecting outwardly beyond the face of the carrier, and pivotally connected to each other in

front of the carrier and to the ends of said bars, said brackets having inwardly projecting portions carrying rollers, grooved bars adjacent the carrier engaged by said rollers to guide the brackets; and platforms connected to the brackets.

In testimony that we claim the foregoing

as our own, we affix our signatures in presence of two witnesses.

EDWIN H. GRANTHAM.
JOHN B. CORNWALL.

In presence of—

CLARK G. ANDERSON,
HAROLD S. GALLOWAY.
